UNITED STATES PATENT OFFICE.

WILLIAM A. LEONARD, OF RIVERSIDE, ILLINOIS.

DESIGN FOR A SPOOL-CABINET.

44,611.

Specification for Design.

Patented Sept. 2, 1913.

Application filed June 13, 1913. Serial No. 773,557. Term of patent 7 years.

To all whom it may concern:

Be it known that I, WILLIAM A. LEONARD, a citizen of the United States, residing at Riverside, in the county of Cook and State of Illinois, have invented a new, original, and ornamental Design for Spool-Cabinets, of which the following is a specification, reference being had to the accompanying drawing, forming part thereof.

The figure shown in the drawing is a perspective view of a spool cabinet showing my new design.

As shown in this drawing, my new design for spool cabinets comprises a base having ornamenteally curved or molded edges, an upright portion having a paneled lower

part for receiving drawers, and a glazed upper part showing an interior rounded or curved spool support. The upright part is made sufficiently high in proportion to its horizontal dimensions so as to give a graceful, pleasing appearance, and is capped by an ornamental cap having curved or molded edges which harmonize with the base portion.

I claim:

The ornamental design for a spool cabinet, as shown and described.

WILLIAM A. LEONARD.
